SAMUEL B. GOLD, OF INDEPENDENCE, MISSOURI, ASSIGNEE TO S. W. LIVINGSTON, OF WASHINGTON, DISTRICT OF COLUMBIA.

INTERNAL-COMBUSTION ENGINE.

1,350,864.

Specification of Letters Patent. Patented Aug. 24, 1920.

Application filed July 17, 1916. Serial No. 109,815.

To all whom it may concern:

Be it known that I, SAMUEL B. GOLD, a citizen of the United States, residing at Independence, in the county of Jackson and State of Missouri, have invented certain new and useful Improvements in Internal-Combustion Engines, of which the following is a specification.

This invention relates to internal combustion engines and my object is to produce a construction whereby such engines can be operated efficiently and reliably with crude oil or other liquid hydrocarbon fuel of low specific gravity. More specifically my object is to produce a construction for causing the hot blasts of the exhaust gases to impinge upon and substantially envelop the casing of the throttle valve of the engine, for the purpose of highly heating said casing and valve and thereby effecting the superheating of combustible gases just prior to the entrance thereof into the compression chamber of the cylinder of the engine. A further object is to produce a construction of the character mentioned, which is simple, strong, durable and inexpensive.

With the objects named in view the invention consists in certain novel and peculiar features of construction and organization of parts as hereinafter described and claimed; and in order that it may be more fully understood reference is to be had to the accompanying drawing, in which:-

Figure 1, is a fragmentary front view of an internal combustion engine embodying my invention.

Fig. 2, is a horizontal section taken on the line II—II of Fig. 1.

Fig. 3, is a vertical cross section taken on the line III—III of Fig. 1.

Referring to the drawing in detail, 1 indicates the head end of the cylinder of an internal combustion engine of any suitable type, 2 is the pipe-way for supplying a combustible mixture to the compression chamber, not shown, of the engine, and mounted upon said pipe adjacent the head of the engine is a casing 3 containing a throttle valve 4, the valve being shown as of the butterfly type, though it will be understood of course, that the special type of valve is unimportant. It will be noticed that the lower member of the pipe-way 2 communicates with the valve chamber at the lower side of the same and that the upper member of the

said pipe-way leads from the upper part of the said chamber to the cylinder at the point where it is controlled by the customary or any preferred type of intake valve, not shown.

The valve casing is preferably formed integrally with a hollow housing 5, whose front, top and bottom walls preferably coincide in position with the corresponding walls of the valve casing.

The housing 5 is of length and form to provide a passage 6 extending from a point at one side of the valve casing to a point at the opposite side thereof, the intermediate or throat portion of said passage lying back of said casing, so that hot gases from the exhaust port of the engine, passing through the pipe-way 7, and entering the housing at one side thereof, shall impinge upon the adjacent side wall of the valve casing and then pass along the rear thereof to the opposite side of the said housing, at which point the gases escape through a pipe 8 to the atmosphere, or to a muffler, not shown, of any suitable or preferred type. It will thus be seen that the hot exhaust gases are applied in successive blasts directly upon one of the side walls of the casing and that such hot gases before escaping also come in contact with the back wall and the other side wall of said casing, and that such extended or enveloping contact results in raising the valve casing and the valve therein to a temperature which effects the superheating of the combustible mixture passing through the valve chamber to the cylinder and effectively guards against any congealing of such mixture in said chamber. Because of this a combustible mixture, of which vaporized crude oil or equivalent hydrocarbons is a constituent, can be effectively employed for the operation of an internal combustion engine, the special type of carburetor or other vaporizing device, not shown, being unimportant.

To avoid such rebound of the hot gases from the wall of the casing upon which they impinge as would unduly retard the circulation of such gases, said wall is sloped rearwardly as at 9, and the rear corner of the casing is rounded at the entrance end of the throat or intermediate portion of the passage of the housing.

From the above description it will be apparent that I have produced means for ef-

ficiently superheating the combustible mixture for an internal combustion engine, as it passes the throttle valve, which will be found of advantage in the operation of internal combustion engines with liquid fuel of any specific gravity, and while I have illustrated and described the preferred embodiment of the invention, it is to be understood that I reserve the right to make all changes in the form, proportion, and arrangement of parts which properly fall within the spirit and scope of the appended claim.

I claim:

- 15 In an internal combustion engine the combination of a cylinder, a housing underlying and extending transversely of the cylinder and provided at one end with a gas receiving and at the other end with a gas dis-
- 20 charging opening, an exhaust gas pipe connecting the cylinder with the receiving opening of the housing and a discharge exhaust gas pipe connected with the other end of the housing; said housing having a
- 25 front wall substantially straight and sub-

stantially in line with said openings and a back wall bowed rearwardly from and between said openings, the front wall having a portion projecting rearwardly into the housing to constrict the central portion of the passage thereof and intercept the direct path of travel of the exhaust gases from the exhaust gas supply pipe and deflect them rearwardly through said constricted throat of the passage, said rearwardly projecting portion having a horizontal cylindrical opening extending from front to rear to give access to the valve chamber, a removable plug closing the last named opening, and forming a journal for the valve, and vaporizing fuel supply and discharge pipes communicating with said receiving and discharging openings.

In testimony whereof I affix my signature, in the presence of two witnesses.

SAMUEL B. GOLD.
